UNITED STATES PATENT OFFICE

LOWELL J. SMITH, OF CONNERSVILLE, INDIANA, ASSIGNOR TO STANT MANUFACTURING CO., OF CONNERSVILLE, INDIANA, A CORPORATION OF INDIANA

DESIGN FOR A RADIATOR ORNAMENT

Application filed October 21, 1932. Serial No. 45,438. Term of patent 7 years.

To all whom it may concern:

Be it known that LOWELL J. SMITH, a citizen of the United States, residing at Connersville, in the county of Fayette and State of Indiana, has invented a new, original, and ornamental Design for a Radiator Ornament, of which the following is a specification, reference being had therein to the accompanying drawing, forming part thereof, in which—

Figure 1 is a top plan view of a radiator ornament showing my new design.

Figure 2 is a side elevation of the same.

Figure 3 is a front view of the same.

I claim:

The ornamental design for a radiator ornament, as shown.

In testimony whereof, I affix my signature.

LOWELL J. SMITH.
